COMBINED WRIST WATCH AND MIRROR

Alfred E. Ischinger, Reading, Pa.

Application March 19, 1958, Serial No. 50,098

Term of patent 3½ years

(Cl. D42—8)

FIG. 1.

FIG. 2.

FIG. 3.

FIG. 4.

Figure 1 is a front elevational view of a combined wrist watch and mirror, showing my new design;

Fig. 2 is an end elevational view looking from the left of Fig. 1, with the bracelet element omitted for convenience of illustration;

Fig. 3 is a rear elevational view with the bracelet element omitted for convenience of illustration; and

Fig. 4 is a top plan view.

The dominant features of my design reside in the portion shown in full lines.

I claim:

The ornamental design for a combined wrist watch and mirror, substantially as shown and described.
